UNITED STATES PATENT OFFICE.

JOSEPH G. FISHER, OF NEWARK, NEW JERSEY.

BRACELET.

Application filed August 9, 1923. Serial No. 656,536.

To all whom it may concern:

Be it known that I, JOSEPH G. FISHER, a citizen of the United States, and a resident of Newark, county of Essex, and State of New Jersey, have invented certain new and useful Improvements in Bracelets, of which the following is a specification.

This invention relates to an improved bracelet or similar article of jewelry of the link type which can be economically manufactured and easily assembled and thus saves labor and time in such assembly. The bracelet when assembled is very flexible and presents a neat close appearance.

15 The invention is illustrated in the accompanying drawing in which Figure 1 is a face view of part of a bracelet made according to my invention and Figure 2 is a back view thereof. Figure 3 is an enlarged section taken on 3-3 in Figure 1, and Figure 4 is an enlarged back view. Figure 5 is a section on line 5-5 in Figure 3 and Figures 6 and 7 are perspective views of the two pieces that go to make up a link.

20 25 The bracelet consists of links 10 which are hingedly connected together where they abut. Each link consists of two pieces, a face plate 11 which can be suitably ornamented and side pieces 12 which are connected together by a bar 13 but in the case of short links such as square links the bar can be dispensed with. The bar however in the longer links strengthens the link and is also convenient in that the side pieces 30 35 are handled together as one piece.

The face plate has a lip 14 one end of which is offset from the face and is bendable. The side pieces have opposed studs 15 which are struck up on the side pieces and when the side pieces are in place these studs are in line. The studs are spaced from the top edges of the side pieces so that when the face plate is soldered on the side pieces, the clearance allows the insertion of the lip 14 of the next link. The links are successively secured to the next one by passing the lip 14 of one around the studs of the next one and bending or crimping the lip to form a knuckle as at 16 and this with studs 15 acts as a hinge.

40 45 50 A bracelet constructed in this way is light and at the same time well braced throughout. It will be understood that the making of the link from the face plate and side plates is subject to modification but the complete assembly of each link is accomplished before it is secured to the next one in fact in practice a large number of links is usually available before manufacture of the bracelet is started.

55 60 I claim:

In a link bracelet a link having open ends with opposed studs on the inside at one end and a lip on the other end and disposed so as to be crimped around the studs on the next adjacent link.

65 In testimony that I claim the foregoing, I have hereto set my hand, this 6th day of August, 1923.

JOSEPH G. FISHER.
